UNITED STATES PATENT OFFICE.

FERDINAND C. BRETSNYDER, OF ST. LOUIS, MISSOURI.

OIL BURNER.

Application filed January 17, 1919, Serial No. 271,605. Renewed March 5, 1923.

To all whom it may concern:

Be it known that I, FERDINAND C. BRETSNYDER, a citizen of the United States of America, and a resident of the city of St. Louis and State of Missouri, have invented 5 certain new and useful Improvements in Oil Burners, of which the following is a specification.

The primary object of the invention is to 10 provide an improved oil burner, whereby the oil is fed thereto by gravity and which can be used in connection with furnaces, stoves and the like.

Another object of the invention is to provide 15 an improved oil burner, whereby all of the air currents that are admitted to the combustion chamber of the burner are directed on the oil from different points thereby assuring a proper co-mingling of the 20 gases arising from the oil.

A still further object of the invention is to provide an improved means for cooling the parts of this improved burner from the intense heat, thus preventing burning out of 25 the parts of the burner.

Other and further objects will appear in the specification and be specifically pointed out in the appended claims, reference being had to the accompanying drawings exemplifying the invention, and in which—

Figure 1 is a vertical section of a portion of a furnace showing this improved burner located above the grate bars.

Figure 2 is an enlarged plan view of the 35 burner.

Figure 3 is a vertical section taken on the line III—III of Fig. 2.

Figure 4 is an enlarged horizontal section 40 taken approximately on the line IV—IV of Fig. 3.

Figure 5 is an enlarged horizontal section taken on the line V—V of Fig. 3.

Referring to the drawings this improved 45 burner comprises a circular housing 1 having a horizontal annular flange 2 formed therearound on the outside thereof adjacent the bottom, and concentrically arranged in said housing is a bowl 3, and there being an annular passageway 6 formed between the bowl and the inner wall 8 of the housing. The upper portion of the housing 1 is turned inwardly, thereby forming a convex-shaped 50 top portion 7, the inner wall of which adjoins the wall 8 of the bowl 3. Formed in the top portion 7 are a plurality of openings

10, each opening having a neck 11 formed therearound.

Centrally arranged in the bowl 3 and extending upwardly therein is an annular flange 12 in which is formed a passageway 13, 60 and centrally arranged adjacent the lower end of said flange and supported thereto by ribs 14 is a threaded bushing 15, there being passageways 16 formed between said ribs. Mounted in the lower end of said bushing 15 65 is a vertically arranged pipe 17, and mounted in the upper end of said bushing and in communication with said pipe 17 is a hollow stem 18, having at its upper end a spreader 19, the passageway 20 formed in said spreader 70 communicating with the top thereof. This spreader 19 is of a mushroom shape and has a plurality of annular grooves 21 formed on its upper face.

Mounted above the spreader 19 is a down-draft dome 22, and radially arranged horizontally from said dome are a plurality of draft tubes 23, the outer ends of said tubes turning downwardly as designated at 24. The seating portions 25 of said tubes engage 80 respective necks 11 which are formed around the respective openings 10.

As shown in Fig. 1, this improved oil burner can readily be mounted in a furnace above the ashpit 26, in which the central 85 grate bars are removed, and the annular flange 2 of the housing 1 will engage and rest on the adjacent grate bars 27. It is preferable, however, to place a sheet of material 28 above the remaining grate bars on 90 which is placed a plastic filling material so as to create a draft from the ash pit into the proper channels relative to this improved burner.

In the operation of this improved device 95 oil is supplied to the vertical pipe 17 from the supply pipe 29 which leads from a source of supply, that is elevated on a plane above the burner, and the oil upon travelling up the passageway 20 of the spreader 19 will 100 travel over the mushroom shaped surface of the spreader. Of course, it is to be understood when starting the fire that a flammable material is mounted in the bowl 3 and ignited, and the oil upon leaving the spreader 105 will engage the material and become gaseified and ignite.

After the fire has been started the air is entrained from the ash pit of the furnace through the open bottom 30 of the housing 110

1, the air currents dividing, some of which will traverse the annular passage 6, and enter the draft tubes 23, the currents from all of said tubes merging in the dome 22 and discharging on top of the oil spreader 19. The other currents of air will be entrained through the passages 16 and annular passageway 13, and upon leaving said annular passageway 13 will engage against the under side of the spreader and be deflected downwardly through the passageway 32 which is formed between the flange 12 and the depending lower portion of the spreader, thereby entering the bowl 3 and travelling on upwardly between the depending wall 8 and the spreader.

The air currents following the passageways as described will all engage the oil flowing over the top of the spreader 19, and since the air currents will be somewhat heated, due to travelling the tortuous passageways, the air currents upon striking the oil will convert the oil into gases so that no oil will drip from the depending portions of the spreader, as the oil travelling over the spreader will be converted into a gas before it reaches said depending spreader edge.

The grooves 21 formed on the upper surface of the spreader will tend to retard the oil in its downward flow and, in as much as the air currents are always traversing the annular passage 6, draft tubes 23 and dome 22, the metallic parts forming said passageway and tubes will be kept in a relatively cool condition so that they will not burn out from the intense heat created in the combustion chamber 33 which is formed within the depending wall 8.

It is to be noted that the upper edge 34 of the flange 12 is on a plane below the upper edge of the top portion 7. This is for the purpose of allowing the oil to travel over said upper edge 34 into the passageway 13, providing oil has been allowed to run while combustion has not been in effect in the combustion chamber. This overflowing oil will travel down the vertical pipe 17 to the drip pan 35.

For preventing the spreader 19 from be-

ing mounted too closely against the upper edge 34 of the flange 12, a lug 36 is formed on the underside of said spreader, said lug being adapted to engage said upper edge 34 of said flange.

What I claim and desire to secure by Letters Patent, is:—

1. An oil burner comprised of a housing having an inner and an outer circular wall, said walls being joined to each other by a curved top wall formed integral therewith, said inner wall curving inwardly at its lower end thereby providing a bowl within said inner wall in which the curving of the lower end of said inner wall forms a bottom to the bowl, a tubular extension formed integral with the bottom of said bowl forming a passageway to said bowl from therebelow, an oil spreader extended above said extension having its lower edge extended on a plane below and on the outside of the upper end of said extension, said walls of said housing forming an annular passageway, said upper wall of said housing having a plurality of openings, and there being means provided for entraining air currents from said openings of said upper wall to the top of said spreader.

2. An oil burner comprising a housing open at its lower end, a circular walled bowl portion centrally arranged in said housing formed integral therewith, an annular passage way formed between said bowl portion and said housing, said housing at its upper end being curved inwardly thereby providing an annular wall depending to said bowl portion, said wall being curved inwardly at its lower end and forming a bottom to said bowl portion, said bowl portion having an opening centrally arranged therein and an integrally formed annular flange extending upwardly therearound, an oil spreader arranged above said flange, said housing at its upper end having a plurality of openings which are arranged on a plane above the upper edge of said flange, and a plurality of removably mounted down-draft tubes leading from said openings of the top of said housing to the top of said spreader.

FERDINAND C. BRETSNYDER.
